ORE CRUSHING MACHINE

Mitchel Tveit, Tacoma, Wash.

Application May 15, 1933, Serial No. 671,164

1 Claim. (Cl. 198—151)

This invention relates to machines for breaking and crushing rock, especially ore, and has for its objects to provide such a machine as will perform this work with the least expenditure of power; which will greatly increase the rate of crushing the ore; which will be substantially automatic in its action; which will be continuous in its action; which will permit the continuous escape of fine rock powder as it is produced; which is cheap to build and to operate; and which will effectively reduce the hardest rock to a fine powder.

I attain these and other objects by the devices, mechanisms, and arrangements illustrated in the accompanying drawings, in which—

Fig. 1 is a vertical longitudinal section of my improved ore crushing machine; Fig. 2 is a partial transverse section of the upper part thereof; Fig. 3 is a similar view of the lower part thereof; Fig. 4 is a side elevation of the upper part thereof, showing the driving mechanism; Fig. 5 is a side elevation of one of the buckets, its wheels having been removed and indicated by dotted lines; Fig. 6 is an elevation of one end of one of the buckets, showing one wheel removed and showing parts in section to reveal the construction thereof; Fig. 7 is a section of the machine at the upper driven sprocket wheel, showing the buckets as they pass over the sprocket wheel and dump their contents; and Fig. 8 is an elevation of a portion of one of the cables, showing portions of buckets and a cable spreader attached thereto.

Similar numerals of reference refer to similar parts throughout the several views.

Referring to the drawings, it will be seen that my improved ore crushing machine comprises a single structure divided into two main compartments, one compartment comprising the elevating chamber and tank, and the other compartment comprising the falling and crushing chamber. It is intended that the structure be of considerable size, for instance the height of from thirty to sixty feet, a length of from twenty to thirty feet, and a width of from eight to fifteen feet being considered sufficient.

The driving mechanism is preferably mounted on suitable framing outside of the upper end of the structure and comprises a source of power such as the motor 1, which turns the large wheel 2 by means of the belt 3. The wheel 2 is mounted on the drive shaft 4 and is provided with a pinion 5 which meshes with the gear 6 mounted on the countershaft 7. A second pinion 8 is mounted on the countershaft 7 and meshes with the large gear 9 mounted on the sprocket shaft 10. This shaft 10 extends into and across the

upper end of the elevating chamber 11 and carries the two sprocket wheels 12 securely mounted thereon, said wheels 12 being adapted to apply the full force of the driving mechanism to lift on that part of the vertical elevator, hereinafter described, adjacent to the wall 13 dividing the chamber 11 from the falling and crushing chamber 14. An idler shaft 15, with sprocket wheels 16 mounted thereon, is mounted on a higher level than the said shaft 10 and extends parallel thereto across the upper end of the chamber 11 and is adapted to direct the downward moving part of the vertical elevator adjacent to the outer wall of the said chamber 11. Another idler shaft 17, with suitable sprocket wheels 18, is mounted across the structure above the falling and crushing chamber 14 and at a level substantially the same as the idler shaft 15. A third idler shaft 19 is mounted across the lower end of the chamber 11, and carries suitable wheels 20, and is provided with suitable stuffing boxes 21, where it passes through the walls thereof, to prevent the water in the tank formed by the lower part of the chamber 11 from escaping. Suitable adjustment of one of the shafts 15, 17 or 19 may be provided to take up the slack in the elevator.

The elevator comprises a pair of endless parallel cables 22 between which are clamped a series of buckets 23, hereinafter described. These cables 22 lie between the end of the buckets 23 and the respective sprocket wheels. The buckets 23 carry projections adapted to engage the teeth of the sprocket wheels. Suitable spreaders 24 are similarly mounted on the cables 22 between the consecutive buckets 23 and are also provided with sprocket-engaging projections.

Each bucket 23 comprises a cast end piece 25, having an internal flange 26, to each of which the shell plate 27 of the bucket is secured, thus forming a complete bucket structure. This plate 27 is separated from the flanges 26, to which it is secured, by means of thin washers 28, thereby forming a continuous slot 29 between the plate 27 and each end piece 25, through which the water may escape from the bucket and may carry with it the finer particles of rock.

Each end casting 25 is provided with a specially formed vertical flange 30, extending laterally from the end piece 25, and which is provided with a semi-cylindrical straight vertical groove 31, adapted to receive the cable 22. A clamping piece 32 is provided with a groove complementary to the groove 31 and is adapted to be secured to the flange 30 and to clamp the cable 22 to the bucket 23.

Each end casting 25 of the buckets 23 is provided with two projections comprising the pins 33, suitably secured to and extending laterally from the said flange 30 and adapted to receive a small wheel 34 mounted thereon. Preferably roller bearings 35 are interposed between each pin 33 and its wheel 34. The end of the wheel 34 may be closed by a suitable plate 36 to prevent the entrance of grit to its bearings. Also a felt washer may close the inner ends of the bearings to protect them from the entrance of foreign matter. The outer surface of the wheels 34 are grooved to form two flanges 37 which are adapted to engage the sides of the teeth of the several sprocket wheels as they pass thereover, thereby preventing the elevator from slipping off the said sprocket wheels.

The spreaders 24 are provided with similar wheels 34 and are similarly secured to the cables 22.

A pair of rails 38 are mounted in the upper end of the structure between the sprocket wheels 16 and 18, on each side, and are adapted to support the empty buckets 23 as they travel horizontally from the crushing chamber 14 to the elevating chamber 11.

The above-described sprocket shaft 10, on which the lifting sprocket wheels 12 are secured, is also provided with a rotating spill-bucket 39 formed of a series of radial partitions 40 mounted on a central boss 41 and having end closure disks 42. Since this entire structure and the sprocket wheels 12 rotate with the shaft 10 it follows that the several buckets 23 will move substantially uniformly with the several partitions of the spill-bucket 39 and that all materials spilling from the buckets 23 will be caught by the spill-bucket 39 and will be dumped thereby as it turns with the shaft, thus preventing any material from spilling back into the elevator chamber 11.

Thus it will be seen that the elevator comprises a pair of cables 22 to which are clamped, at suitable intervals, the buckets 23, said buckets 23 carrying sprocket-engaging wheels 34 adapted to engage between the teeth of the several sprocket wheels and to operate the elevator through the driven sprocket wheels 12; and that each such bucket 23 is constructed so as to permit the water to escape therefrom through the side slots 29. It will also be seen that the buckets 23 descend vertically into the tank formed at the lower end of the chamber 11, and receive therein water and rocks, and that they pass therefrom vertically to a considerable height and as they rise they permit the water to run back into the tank while the rocks are carried to the top of the chamber 11. Here, it will be seen that the cables turn over the wheels 12 to the right (Fig. 1) and, as they thus turn, the sprocket wheels 12 which engage both ends of each bucket 23 by its wheels 34, turn the buckets over and dump the rocks therefrom. Those rocks which fall before the turning is entirely completed fall into the spill bucket 39 which carries them in the same direction and dumps them, with the other rocks, into the chamber 14.

Now this chamber 14 (Fig. 1) is provided with a very solid floor 43, positioned at a point slightly above the level of the water in the tank at the base of the chamber 11, and inclined downward towards the said tank. The rocks which

are dumped from the buckets 23 fall onto this floor 43 and are broken. As rocks from the next bucket 23 fall to the floor 43 they naturally hit the rocks which have fallen before them. Thus each rock is shattered by the continuous pounding and grinding of other rocks on it and by its own fall on other rocks. As these rocks are thus comminuted they gradually flow down the inclined floor and drop into the water in the tank and into the buckets 23 as they are led past the end of the rock chute 44 from the floor 43, while the smallest particles are released into the water. The chamber 14 is provided with a suitable lining 45, at its lower end, which may be made of rails placed on end, side by side. A gate 46 may be placed at the rock chute 44 to control the flow of rocks from the floor 43 into the tank.

The tank is normally full of water up to a level close to the mouth of the rock chute 44. A spray of water may be directed into the buckets 23 as they leave the water in the tank, as shown at 47 in the drawings.

The tank is provided with a lateral overflow which directs the water into a flume 48. The overflowing water carries with it the lighter comminuted materials. The degree of fineness of such materials being thus carried off by the water depends on the rate of supply of water to the tank. With a low rate of supply of water the materials will be fine enough to pass through a 100 mesh screen while a heavier flow of water will carry off materials which would not pass through a 40 mesh screen.

New rock or ore may be continuously supplied to the machine by dumping it into the crushing chamber 14 by means of a feeding mechanism such as is diagrammatically illustrated at 49 in Fig. 1.

Many variations in my invention may be made without departing from the spirit thereof, as outlined in the appended claim and the machine may be used without water for dry grinding of cement rock or of talc and other materials.

Having, therefore, described my invention, what I claim, and desire to secure by Letters Patent, is:—

An ore elevator comprising a series of pairs of similar spaced sprocket wheels; means for driving one pair of said sprocket wheels; a pair of endless parallel cables, permanently out of contact with said sprocket wheels; a series of buckets clamped to both said cables and spaced at uniform distances apart thereon; clamping flanges formed on the end plates of each bucket and cooperating with clamping plates attached thereto to clamp each cable therebetween, said flanges and plates extending substantially the full depth of the bucket; two pins extending laterally from the upper and lower portions of said clamping flanges on each side of the bucket; double-flanged wheels mounted on all four of said pins and adapted to engage the teeth of said guiding and driving sprocket wheels between the said flanges; intermediate bars, positioned between consecutive buckets; cable-clamping means near the ends of said bars; and similar double-flanged wheels mounted on the ends of said intermediate bars, whereby said cables are adapted to transmit the operating stresses to move the buckets and are held away from said sprocket wheels and are guided along the path of travel.

MITCHEL TVEIT.
